UNITED STATES PATENT OFFICE

156,064

DESIGN FOR A HOUSING FOR A HOUSEHOLD SCALE

Everett C. Young, Chicago, Ill.

Application September 22, 1948, Serial No. 148,710

Term of patent 7 years

(Cl. D52—10)

To all whom it may concern:

Be it known that I, Everett C. Young, a citizen of the United States and a resident of Chicago, county of Cook, and State of Illinois, have invented a new, original, and ornamental Design for a Housing for a Household Scale, of which the following is a specification, reference being had to the accompanying drawing, forming a part thereof.

Fig. 1 is a view in perspective of a housing for a household scale, showing my new design. Fig. 2 is a side view of the housing on a scale smaller than that of Fig. 1. Fig. 3 is a top view of the housing on the scale of Fig. 2, and Fig. 4 is a detail view in elevation of those parts of the housing adjacent the dial opening therein, on a scale larger than that of Fig. 1.

The dominant parts of the design are those appearing in full lines in the drawing.

I claim:

The ornamental design for a housing for a household scale, substantially as shown and described.

EVERETT C. YOUNG.
